UNITED STATES PATENT OFFICE.

OLIVER E. SHEIDLER, OF OLD FORT, OHIO.

ATTACHMENT FOR SWITCH-LOCKS.

1,292,104.

Specification of Letters Patent.

Patented Jan. 21, 1919.

Application filed July 25, 1918. Serial No. 246,704.

To all whom it may concern:

Be it known that I, OLIVER E. SHEIDLER, a citizen of the United States, residing at Old Fort, in the county of Seneca and State 5 of Ohio, have invented a new and Improved Attachment for Switch-Locks, of which the following is a specification.

My invention generally relates to improvements in switches or switch locks of 10 that class commonly used for controlling automobiles or gas engine ignitions, and it is more particularly directed to the production of an attachment of a very simple, and inexpensive nature, especially designed 15 for being applied to switch lock controls for Ford automobiles.

As is well known, the switch locks on automobiles of the type stated are arranged for being operated with a peculiarly designed 20 key for that particular type of switch lock mechanism, which form of key is adapted for operating the switch lock equipments on all new Ford cars.

To provide for arranging the switch 25 mechanism of the kind stated so that a special or individual key may be used for operating the switch, it has been a common practice to combine a Yale or other combination lock mechanism with the said stated 30 switch lock mechanism so that only an individual key can be used for operating the switch lock.

To apply a Yale or other similar type of lock to a Ford car switch lock is more or 35 less expensive and requires a careful fitting of the parts.

The main purpose of my invention is to provide an attachment that can be made at a very low cost and in which the parts are so 40 designed that they may be quickly and easily applied onto a switch box without the need of screws or other like fastening means.

With further objects in view, that will hereinafter appear, my invention consists 45 of an attachment for the purposes stated that embodies the peculiar features of construction and arrangement of parts to be first explained in detail, specifically pointed out in the appended claims and illustrated 50 in the accompanying drawings, in which:

Figure 1 is a cross section of a preferred form of my improved attachment, so much of a switch lock mechanism of the general type, before mentioned, being shown that

illustrates a practical application of my said 55 invention, the attachment being shown in position for being slid over the switch lock box, the key being also shown in position for being inserted in the key socket, the attachment being shown at its fully applied 60 position in dotted lines.

Fig. 2 is a detail section of parts of the switch lock with my attachment applied, the key being shown in position for turning the switch to close in the magneto or the battery 65 circuits.

Fig. 3 is a perspective view that illustrates a modified form of my attachment hereinafter particularly referred to, the switch box being also illustrated in this figure to show the manner in which the modified form of my attachment may be applied 70 onto the front plate of the switch box.

Fig. 4 is a face view of the attachment applied to the switch box and illustrates the 75 cup-shaped or preferred form, the position of the key being shown in full lines and the extent of lateral throw of the key to close the magneto or battery circuits being indicated in dotted lines.

In the drawings, the switch comprises a casing 1 of insulated or other suitable material and in which is contained the stationary contacts and a movable contact 3 mounted on a switch member 5, the latter in 85 turn being mounted on a collar 6 that is rotatably journaled on a socket bearing 7 attached to the base portion 10 of the casing 1.

The collar 6 has a pair of oppositely disposed recesses 8—8 and the front or recessed end of the said collar 6 projects through a central opening 9 in the front plate 11 of the switch lock housing for receiving the key tangs of the conventional type of key now 95 used in connection with the form of switch lock mechanism described, the latter being of a well known construction need not be further referred to.

My improved attachment comprises a 100 front plate 12 which, in the preferred form shown in Figs. 1 and 2, forms an integral part of a cup-like body shaped for being pushed over the switch housing, the said cup-like body in practice being so formed 105 that, when pushed onto the housing, it frictionally engages such housing so that it cannot be readily removed without the use of

some special tool or implement, it being understood that the cup-shaped body is formed as stated so that it may be securely attached onto the switch lock housing without the need of screws or other like fastening means.

The cup-shaped body is preferably formed of a stout resilient sheet metal and approximately centrally thereof it has a key slot 13, 10 the circular portion 14 of which receives a longitudinally grooved key socket 15 provided with a collar 16 for holding it from passing through the said key hole portion 14.

When the cup-like body is slipped onto 15 the switch housing, as is indicated on Fig. 1, and pushed in against the front plate of the housing, as indicated in dotted lines on the said Fig. 1, the key socket 15 projects into and is rotatable within the socketed 20 bearing 7 on which the collar 6 is rotatably mounted, as is clearly shown in Fig. 2, by reference to which it will be readily apparent that by using a key 60 shaped as shown, the latter may be easily inserted into 25 the lock by bringing the key socket 15 in line with the key slot in the front plate of the cup-shaped body and, when thus positioned, the key tang 17 will ride along the outer edge of the socketed bearing 7 and 30 project into one of the opposite grooves 8 in the collar 6 that carries and rotates with the switch member 5, it being understood the key need be turned but a short distance in either direction to effect the closing of the 35 magnet or battery circuit, as is indicated on Fig. 4, from which it will be observed that the key, when at the midway position, is on the "off" point.

With my attachment, when the cup-shaped 40 body is used, the extent of projection of the body onto the switch housing may be varied to provide for the use of keys whose unlocking tangs are varied to suit the distance space between the front plate of the body 45 and the grooved face of the collar 6.

Instead of making the attachment cup shaped, as in Figs. 1 and 2, a single plate 18 may be used, as shown in Fig. 3, the said plate being of the configuration of the 50 front plate of the housing.

When the single plate 18 is used, the said plate has apertures 19—19 to aline the screw apertures in the front plate of the housing and the same screws that secures the housing plate may be used to fasten the plate 55 18 in position.

From the foregoing taken in connection with the drawings, the complete construction, the manner of its use and the advantages of my invention will be readily apparent.

The same can be very cheaply made and easily applied to the Ford type of switch-lock devices by any one, without the need

of special tools for the purpose, the same 65 offering a substantial substitute for the expensive Yale types of locks generally applied to the said form of switch mechanisms to adapt the same for being opened by an individual key. 70

What I claim is:

1. In combination with a locking switch of the character described, which switch includes a housing, a bearing mounted substantially centrally of the housing base, a 75 collar rotatably mounted on the bearing having key receiving grooves in its outer face, the said housing including a face plate provided with an aperture into which the grooved face of the collar projects; of a 80 cover plate adapted for being mounted over the housing face plate, the said cover plate being provided with a key hole aperture that alines the aperture in the housing face plate, a longitudinally grooved socket whose 85 front end projects into the opening in the cover plate and is adapted for extending into the socketed bearing member of the switch when the said cover plate is applied, and a key for coöperating with the key socket 90 and the key slot in the cover plate, the said key including a tang adapted for interlockably engaging one of the grooves in the rotatable collar on which the control member of the switch is mounted. 95

2. The combination with a switch lock of the character stated, which lock includes a casing having a base, a bearing mounted on the base, the free end of the bearing being formed with a longitudinal socket, the said 100 casing including a face plate having a substantially centrally disposed aperture, a collar rotatably mounted on the socketed bearing, the said collar having oppositely disposed radial grooves in the front face, the 105 said front face being projected into the opening of the face plate of the casing and a contact maker mounted on and rotatable with the collar; of a cup-like member shaped for sliding over and frictionally engaging 110 and covering the said casing, the said cup-shaped member having a key hole slot that alines the opening in the casing front plate, a longitudinally grooved key socket whose 115 front end engages in the key hole slot of the cup-shaped member and whose other end is adapted for projecting into the socket of the bearing on which the switch carrying collar is rotatable mounted, and a key device adapted for being passed through the said 120 key socket and having a tang for interlockably engaging the inner face of the cover plate and the grooved switch turning collar.

3. As a new article, an attachment for 125 switch lock mechanisms of the general character stated, comprising a cup-like member of resilient metal having the external shape of the switch housing, whereby to friction-

ally slide over and cover the front plate of the housing, the front portion of the said member having a key hole aperture, a longitudinally grooved key socket, the outer end 5 of which is adapted for being rotatably mounted in the key hole aperture in the said member and whose inner end is adapted for

being rotatably mounted in the switch lock mechanism, and a key coöperating with the said key socket and shaped for interlockably 10 engaging the switch mechanism to shift the same to the circuit closing position.

OLIVER E. SHEIDLER.
